ROTARY SWITCH

Harold P. Mixer, Frankfort, N. Y., assignor to
Remington Rand Inc., Buffalo, N. Y., a corporation of Delaware

Application December 7, 1935, Serial No. 53,285

4 Claims. (Cl. 175—375)

This invention relates to switches, and particularly to switches having wipers adapted to be stepped in unison with the wipers of other switches.

5 It frequently becomes necessary to employ switches having a number of contacts differing from the number provided in standard switches. Switches having the desired number of contacts may be made to order, but the cost is high. This 10 cost may be avoided in some instances, as it sometimes happens that a switch having the desired number of contacts can be obtained if two or more standard switches are combined to form a single switch. To combine standard switches in this way, the wipers of the combined switches must be stepped in unison, and thus far the difficulty of doing this has made the combination of standard switches impracticable for the purpose mentioned.

20 It is an object of this invention to overcome this difficulty by causing the wipers of a number of combined switches to be stepped in unison.

It is a further object of this invention to operate the stepping magnets of the combined 25 switches at the same time, and also to release them at the same time in order that the wipers of the combined switches may be stepped in unison.

It is an additional object to hold the wipers in 30 each of the combined switches in fixed angular relation to the wipers of the other switches.

The invention resides in the means for simultaneously operating the stepping magnet in each of the combined switches, and subsequently releasing them simultaneously, whereby the wipers of the combined switches are stepped in unison, and in the means for retaining the wipers in each of the switches in fixed angular relation to the wipers in the other switches.

40 Briefly described, the invention consists of two or more rotary switches each having a plurality of wipers, a bank contact assembly with which the wipers cooperate and a stepping magnet, and means for alternately interrupting and completing the operating circuits of the stepping magnets in all of the switches whereby the wipers of the switches are stepped in unison.

Other objects of the invention will appear when 50 the detailed description, which follows, is taken in connection with the appended claims and with the drawing, in which:

Fig. 1 shows a plan view of one of the combined switches;

Fig. 2 shows in elevation, a pair of combined

switches with the bank contact assembly omitted for the sake of clearness of illustration, and

Fig. 3 shows a chain circuit for controlling the stepping magnets of the combined switches.

For the purpose of illustration, the invention is 5 shown applied to combined switches of the type shown in patent to John Erickson, No. 1,794,888, dated March 3, 1931, but it is to be understood that the invention is applicable to switches of other types. As the combined switches are similar 10 in construction, a description of one will suffice for both. This switch is described in no more detail than is necessary to an understanding of the present invention, and for a detailed description of its structure, reference is made to 15 the above mentioned patent.

A bank of contacts, indicated generally by 1 (Fig. 1) has cooperating with it a wiper 2. The switch is provided with six of these wipers, as 2-7, inclusive, (Fig. 2) and it is to be understood 20 that each wiper cooperates with a corresponding bank of contacts, although but one of these contact banks is shown in the drawing. The banks of contacts are suitably insulated from one another and are mounted in a bank frame 8 25 which is adjustably secured to a switch frame 9, by means of which the switch may be attached to a supporting member (not shown). The wipers 2-7 inclusive, are likewise insulated from each other and are mounted on a common spindle 10 which is rotatably pivoted in the switch frame 9.

The ratchet wheel 11 and likewise the wipers 2-7 inclusive, are adapted to be driven by a stepping magnet 12, secured to the switch frame 9. 35 When the magnet is energized, it attracts the armature 13, which is pivoted on a pin 14 secured to the switch frame 9, and the top end of the armature is moved laterally against the tension of a spring 15. When this movement of the 40 armature occurs, the pawl 16, carried by the armature, is caused to engage another tooth in the ratchet wheel 11 by the pawl spring 17 and an arm 18 on the armature 13 opens the interrupter springs or contacts 19. When the magnet 45 is de-energized, the spring 15 draws the armature and likewise the pawl 16 to its former position. The return movement of the armature closes the interrupter contacts 19. The pawl 16 in returning to its normal position advances the 50 wipers 2-7, inclusive, into engagement with the next set of contacts. This operation may be repeated as often as desired, and the wipers successively advanced over the contacts of these associated contact banks. The tension of the 55

spring 15, which returns the armature 13 to its normal position, may be adjusted by means of the adjustable member 20, which is provided with a slot adapted to receive a bolt 21 secured to the switch frame 9. The adjustable member is prevented from being rotated about this bolt under tension of the spring 15 by means of the pivot 14. A stop pawl 22, secured to the switch frame 9, serves to hold the wipers 2-7, inclusive, in engagement with the contacts to which they were last stepped.

The spindles 10 and 10' in each of the combined switches are mechanically coupled to hold the wipers of each of these switches in fixed angular relation. The coupling means comprise rods 23 and 24 extending through openings in the spindles 10 and 10', respectively, and a tie member 25 which serves to strap these rods together. The tie member is provided with slots 26 and 27 which allow the spindles 10 and 10' a suitable amount of lateral movement.

Referring to Fig. 3, there is shown the chain operating circuits for the stepping magnets 12 and 12' of the combined switches. The operating circuits of the stepping magnet 12 extend through the interrupter contacts 19 of the same switch and also through the interrupter contacts 19' of the other switch, while the operating circuits of the stepping magnet 12' of the other switch extend through the interrupter contacts 19' of the same switch and also through the interrupter contacts 19 of the other switch. When the stepping magnet 12 is operated and the interrupter contacts 19 open, neither stepping magnet releases until the interrupter contacts 19' open. When the latter contacts open, both stepping magnets 12 and 12' release, causing the pawls, as 16, to step the wipers, as 2-7, inclusive, of each switch. As soon as one of the stepping magnets 12 or 12' releases, the interrupter contacts of the same switch close, and operating circuits for both stepping magnets are again completed with the result that a new cycle of operation for the switches is begun.

In this way, the wipers of the combined switches are stepped in unison by the alternate interruption and completion of the stepping magnet operating circuits; while the coupling between the switch spindles holds the wipers of the switches in fixed angular relation. It is to be understood that the invention could be readily modified to permit the combination of a larger number of switches.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. The combination of a pair of step by step switches, each provided with a plurality of wipers and a stepping magnet therefor, means responsive to the energization and deenergization of each of the stepping magnets for stepping the wipers, and interrupter contacts interacting with

each of the stepping magnets, the interrupter contacts in each switch being included in an operating circuit of the associated stepping magnet in the same switch and in an operating circuit of the stepping magnet of the other switch whereby the stepping magnets are simultaneously energized under control of the interrupter contacts in either switch and simultaneously deenergized under the joint control of the interrupter contacts in the several switches to step the wipers of the switches in unison.

2. The combination of a pair of step by step switches, each provided with a plurality of wipers and a stepping magnet therefor, means responsive to the energization and deenergization of each of the stepping magnets for stepping the wipers, and interrupter contacts adapted to be opened upon the energization of each of said magnets and to be closed upon its deenergization, the interrupter contacts in each switch being included in an operating circuit of the associated stepping magnet in the same switch and in an operating circuit of the stepping magnet in the other switch whereby the stepping magnets are simultaneously energized upon the closure of the interrupter contacts in either switch and simultaneously deenergized upon the opening of the interrupter contacts in both switches to step the wipers of the switches in unison.

3. The combination of a pair of step by step switches, each provided with a plurality of wipers and a stepping magnet therefor, means responsive to the energization and deenergization of each stepping magnet for stepping the wipers, and interrupter contacts interacting with each stepping magnet, the interrupter contacts in each switch being included in an operating circuit of the associated stepping magnet in the same switch and in an operating circuit of the stepping magnet of the other switch whereby the stepping magnets are simultaneously energized upon the closure of the interrupter contacts in either switch and simultaneously deenergized upon the joint opening of the interrupter contacts in the several switches to step the wipers of the switches in unison, and means for holding the wipers of the several switches in fixed angular relation.

4. The combination of a pair of step by step switches, each provided with a plurality of wipers, a spindle carrying said wipers and a stepping magnet therefor, means responsive to the energization and deenergization of the stepping magnet for stepping the wipers, and interrupter contacts interacting with each stepping magnet, the interrupter contacts in each switch being included in an operating circuit of the stepping magnet in the same switch and in an operating circuit of the stepping magnet of the other switch whereby the stepping magnets are simultaneously energized upon the closure of the interrupter contacts in either switch and simultaneously deenergized upon the joint opening of the interrupter contacts in the several switches to step the wipers of the switches in unison, and coupling means connecting the spindles of said switches to hold the wipers carried thereby in fixed angular relation.

HAROLD P. MIXER.
